UNITED STATES PATENT OFFICE

ABILIO MARIA DE SILVA GREAVES, OF NEW YORK, N. Y.

DESIGN FOR A BOOK COVER

Application filed March 9, 1931. Serial No. 39,002. Term of patent 7 years.

To all whom it may concern:

Be it known that I, ABILIO MARIA DE SILVA GREAVES, a citizen of Portugal, residing at New York, in the county of New York and State of New York, have invented a new, original, and ornamental Design for Book Covers, of which the following is a specification, reference being had to the accompanying drawing, forming part thereof.

The figure is a plan view of a book cover, showing the front and back of my new design.

I claim:

The ornamental design for a book cover, as shown.
Signed at New York, New York, this 6th day of March, 1931.

ABILIO MARIA de SILVA GREAVES.
